(57) CLAIM

The ornamental design for a guitar pickup, as shown and described.

DESCRIPTION

FIG. 1 is a top perspective view of a guitar pickup showing the new design.

FIG. 2 is a right side view of the guitar pickup shown in FIG. 1.

FIG. 3 is a left side view of the guitar pickup shown in FIG. 1.

FIG. 4 is a top plan view of the guitar pickup shown in FIG. 1.

FIG. 5 is a bottom plan view of the guitar pickup shown in FIG. 1.

FIG. 6 is an end view of the guitar pickup shown in FIG. 1; and,

FIG. 7 is an opposed end view of the guitar pickup shown in FIG. 1.

The broken lines illustrate portions of the guitar pickup that form no part of the claimed design.
